UNITED STATES PATENT OFFICE.

FRANK W. CAMP, OF SAN FRANCISCO, CALIFORNIA.

APPARATUS FOR CONCRETING PILES.

1,411,404.

Specification of Letters Patent.

Patented Apr. 4, 1922.

Application filed February 7, 1920. Serial No. 356,967.

To all whom it may concern:

Be it known that I, FRANK W. CAMP, a citizen of the United States, and a resident of the city and county of San Francisco, State of California, have invented new and useful Improvements in Apparatus for Concreting Piles, of which the following is a specification.

The object of my invention is to provide a sectionalized form which may be assembled about the pile and above the water line, and within which form a suitable mixture, as of concrete, may be placed, and the form then allowed to descend with its contained concrete coating material around the pile to a point below the mud line. The concrete is then allowed to set and the form subsequently removed therefrom, leaving a concrete coating around the pile extending preferably above the water line and below the mud line thus effectually protecting the pile from the ravages of the teredo, or other deterioration, and also providing a reinforcement.

These objects I accomplish by assembling around the pile a sectionalized form, the individual sections of which are joined together at matching joints and with suitable holding means, the lowermost sections being provided with means whereby a bottom closure from the form to the pile is provided, this latter being of a flexible nature, and for the purpose of supporting the gravel layer and therefore also the cement mixture, the surface of the gravel forms a line of "break" for the concrete after it has set so as to permit the free removal of the said first sections of the form. These first or lowermost sections are preferably assembled above the water line, and a plurality of additional sections are then assembled on top of the said bottom sections, which plurality of forms makes a complete boundary surface around the pile, and at a suitable space therefrom forming a mold for the coating to be applied to the pile. The concrete mixture is then filled into the form on top of the aforesaid gravel layer and the suspension cables by which the form is supported are slowly lowered permitting this first portion of the form, including the bottom section, to descend. Further sections may then be assembled and additional concrete poured therein and the above step repeated until

the bottom section approaches the mud line. At this time, in order to provide a cavity around the pile below the mud line, water jets are caused to impinge against the pile at the mud line, the action of which water jets is to scour the mud away and to clean the body of the pile during the further descent of the form with its contained concrete, and until the desired depth is attained.

It is to be understood that during this lowering process further form segments are assembled in sections on the top of the descending form and additional concrete mixture is placed therein, so that the concrete contained within the completely formed mold is separated at all times from the action of the sea water, and is retained in such condition around the pile, and to the desired depth and height, completely insulating the pile surface from any deleterious effects.

By referring to the accompanying drawings my invention will be made clear.

Fig. 1 illustrates partly in section and partly in elevation the lower member of my form.

Fig. 2 is a plan view of the lower member of the form.

Fig. 3 is an assembly of the lower member with two form sections assembled on top thereof and showing the water jet connections.

Fig. 4 illustrates my form in section and in place around a pile and the way in which it is to be used.

Fig. 5 is a plan view of one of the upper sections.

Fig. 6 indicates the manner of joining the segments to form the section.

Fig. 7 is a detail section of a portion of the lower form illustrating the bottom gasket for supporting and retaining the gravel layer upon which the concrete mixture is to rest.

Fig. 8 is a detail enlarged view, showing the lowest mold section and a water jet nozzle;

Fig. 9 represents a pair of water jet nozzles;

Fig. 10 is a view in side elevation showing the use of a tool to pry apart the mold sections;

Fig. 11 is a sectional plan view, illustrating the manner in which the mold sections open;

Fig. 12 is a sectional plan view illustrating the position assumed by the parts of the lowermost mold section when open; and

Fig. 13 illustrates in side elevation the 5 separated position of the same parts.

Throughout the figures similar numerals refer to identical parts.

The pile to be coated with concrete, is indicated by the numeral 1 (see Fig. 4), which 10 pile is presumed to be in place within the mud or sea bottom 4, and to extend above the water surface 3. It is desired to provide a concrete covering around the said pile extending below the mud line, or water bottom 15 4. The lower section which is to contain the gravel layer, or sand gasket, 5, is indicated in detail at Figs. 1 and 2, in which the two principal segments are indicated by the numerals 6 and 7, and which are to be assembled together as indicated at Fig. 2, as 20 by pins and links 8, 9, 10 (see also Fig. 6) or other suitable locking connections.

The bottom sections 6 and 7 are provided with a plurality of hinged members arranged 25 radially (as indicated in Figs. 1 and 7 by the numeral 11). These are made of substantially rigid and heavy material to adequately support the desired weight of concrete mixture, and upon the hinged 30 leaves 11 I prefer to form a plurality of relatively thin overlapping flexible segments 12. Above these leaves, preferably made of thin metal, I secure the two annular canvas segments 13, 14, the ends of which overlap, 35 as indicated by the dimension line at 15 (Fig. 2) when the segments 6 and 7 are assembled.

Suitable reinforcement for the cylindrical segments 6 and 7 is provided by the annular rings 16 and 17 parted on the joints 18, 19. 40 This bottom section assembled around the pile 1 and preferably above the water line, is supported by the holding means 20, 21 actuated from the winch 22, and is now filled with a layer of gravel 5. Above the said 45 bottom section, and about the periphery thereof is now to be assembled the form section 22, 23, 24, 25 composed preferably of the two segments 22, 24 hinged at 26, and 23, 25 hinged at 27, and which segments are 50 provided with assembling and locking means on each side as 8, 9 and 10, previously described.

I prefer to insert a packing of loose material, as a rubber gasket, between the assembling joints, as indicated by 28; and to make the forms of wood so that they will readily float when disassembled after the concrete has set, but it will be understood that the forms may be made in metal if desired without departing from my invention.

Reinforcing rings may also be provided around all the segments as 16, 17 if desired.

After assembling one or more of the segments 22, 23, 24, 25 on the bottom section 6, 7 and 65 about the pile above the water surface and

on top of the gravel body 5, the concrete is to be poured at 29, thus forming a layer of plastic material above the water line, retained in shape and position by the assembled portion of the form and above the water 70 line. The said sections containing the plastic material are now to be lowered and additional form segments as 30, 31 assembled thereabove, and additional concrete filled therein, as the form is lowered by the chains 75 or cables 20, 21 actuated from the winch 22.

As the mud line 4 is approached by the descending form containing the concrete, water pressure is turned on as through the pipes 32, 33 (see Fig. 4) from the pump 35 taking its suction through pipe 36, or other suitable source of water pressure may be utilized for the purpose of establishing water jets under pressure as from the pipes 37, 38, 39, 40, Fig. 2, which are herein shown as extending downwardly from the ends of lateral branch pipes connected with pipes 32, 33, said pipes 37, 38, 40 and 41 passing through openings in the lower flange of the form segments and being supported thereby. The action of these water jets as the form descends toward the mud line 4 will be a scouring action against the pile surface removing the mud and accumulated material therefrom, as in the direction of the arrows 90 41, 42 of Fig. 4, and permitting the descending form with its contained concrete to sink below the mud line 4, the necessary additional form segments being assembled into sections of any length required so that the body of the concrete will extend well above the water surface 3 and to the level 43. The form is now to be retained in the latter position as by the cables 20, 21 and winch 22, until the body of concrete has set and it will be seen that the supporting base 44 for the winch 22 and pump 35 should preferably be anchored to the pile 1, as by the pin 45, thereby preventing movement of the form with respect to the pile during the setting period. 100 110

After the concrete has sufficiently set, the form is removed by withdrawing the series of pins 8, 8 . . . , as by the chains 46, and a wedge shaped tool then being inserted on either side of the joint 47, which continued 115 through the several sections will cause the form segments to split away from each other relieving themselves from the set concrete. The entire structure will now float, if made of wood, or may be withdrawn by the cables as 120 20, 21, the several segments being temporarily retained together as by the hooks 48. The several segments as 22, 24 and 23, 25 will more readily free themselves because of the hinges as 26, 27, and the bottom section 125 6, 7 will readily free itself because of the loose gravel body 5, no part of the concrete being in contact with the hinged bottom and canvas member 13, 14. The form is now ready for assembly on another pile. 130

Particular attention is directed to the scouring action of the water jets and their function in providing a channel or opening around the pile and below the mud surface
5 to secure the efficient placing of the concrete coating below the mud line to any depth required and to facilitate the operations that are carried on entirely above the water line, and the result secured of an efficient concrete
10 coating which expands throughout the submerged surface and beyond the water surface which heretofore contacted with the pile.

I claim:

15 1. A form for molding concrete around piles consisting of a plurality of annular segments formed to enclose an annular space surrounding the pile, and to be assembled in a complete mold form and having continuous joints therethrough parallel with the axis of the pile; a plurality of locking means for said joints, and operating connections for disassembling said locking means from above the water line whereby the form may
20 be separated after the concrete has been molded therein and set by wedging apart the sections along the said joint line.

25 2. A form for molding concrete around piles consisting of a plurality of annular segments formed to enclose an annular space surrounding the pile, and to be assembled in a complete mold form and having a continuous joint therethrough parallel with the axis of the pile; a plurality of locking means for
30 said joints, and operating connections for disassembling said locking means from above the water line whereby the form may
35 be separated after the concrete has been

molded therein and set by wedging apart the sections along the said joint line, in combination with water circulating means at the bottom of and exterior to said form, as and for the purpose set forth. 40

3. A form for molding concrete under water around a pile consisting of a plurality 45 of molding segments which may be assembled in annular form, said segments provided with a plurality of relatively stiff hinged members extending radially inward; a plurality of flexible overlapping leaves 50 supported by said hinged members and substantially closing the bottom of the assembled form to the pile surface; and an annular layer of flexible material above said leaves constructed and adapted to support a layer 55 of inert material.

4. A form for molding concrete under water around a pile consisting of a plurality of molding segments which may be assembled in annular form, said segments provided with a plurality of relatively stiff hinged members extending radially inward; a plurality of flexible overlapping leaves supported by said hinged members and substantially closing the bottom of the assembled 60 form to the pile surface; and an annular layer of canvas above said leaves constructed and adapted to support a layer of inert material, and a layer of granular material 65 above said canvas forming a bottom surface 70 on which and against the surface of the pile thereabove concrete may be formed.

In testimony whereof, I have hereunto set my hand at San Francisco, California, this 26th day of January 1920.

FRANK W. CAMP.
